UNITED STATES PATENT OFFICE.

JOHN DE LAMBERT, OF EAST SAGINAW, MICHIGAN.

FURNACE-DOOR OPERATOR.

SPECIFICATION forming part of Letters Patent No. 373,966, dated November 29, 1887.

Application filed September 3, 1887. Serial No. 248,747. (No model.)

To all whom it may concern:

Be it known that I, JOHN DE LAMBERT, a citizen of the United States, residing at East Saginaw, in the county of Saginaw and State of Michigan, have invented a new and useful Improvement in Furnace-Door Operators, of which the following is a specification.

My invention relates to a device for opening the doors of locomotive-furnaces; and it consists in a certain novel construction and arrangement of parts, fully set forth hereinafter, and specifically pointed out in the claims.

In the drawings, Figure 1 is a rear view of an engine-cab, showing my operating device attached thereto. Fig. 2 is a longitudinal section of the same, showing the operating device in side elevation. Fig. 3 is a detail view of the operating device, partly in section, to show the construction thereof.

Referring by letter to the drawings, A designates the door of the furnace, having the pivoted latch B thereon, of the ordinary construction and arrangement, and C represents the floor of the cab.

D represents a bracket secured to the under side of the floor under the free end of the door, and the said bracket comprises the two parallel depending arms d d, secured together at the lower ends by the cross-bar E, and having the spindle F therebetween close to the floor.

G represents a vertical arm notched at the upper end to fit the latch of the door, and having the angle-arm H on the lower end.

g represents a slot in the vertical arm, adapted to receive the spindle F, and when the said spindle is in the upper end of the slot the notch in the upper end of the arm G is below the catch b, (which is at the side of the furnace-opening,) in which the latch B engages to hold the door in the closed position.

It will be readily seen that if the arm G is raised so that the spindle will be in the lower end of the slot g, the latch B will be raised out of engagement with the said catch, and the door would be free to swing open.

The lower end of the angle-arm H is rounded, and is so arranged that in order to press it forward it must slide over the cross-bar E, as the said bar is in the path thereof. Therefore when the attempt is made to press the lower end of the arm H forward it slides over the said bar E, and consequently raises the arm G,

thereby causing it to slide vertically on the spindle F until the latter is in the lower end of the slot g and the latch B raised out of engagement with the catch b. It will be seen that when the lower end of the arm H has passed over the bar E it will swing forward freely, and therefore if the pressure upon the said lower end is continued the upper end of the arm G will swing rearwardly, and the notch g' in the upper end thereof being still in engagement with the end of the latch the door will be swung open. Thus a simply horizontal movement upon the lower end of the angle-arm H will result in first a vertical and then a rearward motion of the upper end of the arm G, thus accomplishing the unlatching and opening of the furnace-door.

I represents an angle-lever pivoted to the under side of the cab-floor in rear of the arm G, the vertical arm K of which is attached to the lower end of the arm H by means of the connecting-rod M, while to the rear end of the horizontal arm L is pivoted the lower end of the pressure-bar N. The said pressure-bar passes through a small opening in the floor of the cab and projects at the upper end slightly above the same, and it will be readily seen that if the said bar is pressed vertically downward the angle-lever will transform the vertical motion into a horizontal motion at the lower end of the vertical arm K, which horizontal motion will be conveyed by the connecting-rod M to the lower end of the arm H.

O designates a spring secured to the under side of the floor of the cab and operating at the free end against the underside of the horizontal arm of the angle-lever, so that the latter is normally held close to the floor of the cab.

It will be seen that when the arm L of the angle-lever is in a horizontal position the lower end of the arm H is in rear of the bar E, and consequently the arm G is in its lowered position. Therefore when the fireman desires to open the door of the furnace he simply presses with his foot upon the upper end of the pressure-bar N and the lower end of the arm H is pressed forwardly. The lower end strikes against the bar E and is raised, thus raising the bar G, which lifts the latch of the door and then throws the latter open.

When the door of the furnace is opened in

the ordinary way by hand, much time is required to accomplish the same, and it must be left open until the fireman has placed the desired quantity of coal on the fire. This allows 5 the outside air to considerably cool the fire and the flues of the boiler, and thus reduce the pressure of steam and consequently the speed of the engine.

When my opening device is in use, the fireman may open the door to insert each shovelful, if desired, and close the same after inserting it, thus reducing greatly the time which the door stands open. Further, the door is more easily opened in this way than in the ordinary way. The pressure pin or rod is placed 15 at about the point where the fireman stands to rake his fire or shovel coal thereon, and it will be readily seen that to simply press his foot upon the rod would occupy less time and is 20 less trouble than to raise the latch and open the door in the ordinary manner.

Having thus described my invention, I claim—

1. The combination, with the door A, having 25 the latch B thereon, of the lifting-arm G, having the notch g' in the upper end to receive the latch B, the said arm being provided with a slot to receive a spindle, the angle-lever I, connected at one end by the bar M to

the lower end of the arm G, and the pressure-bar N, attached to the other end of the lever, and adapted to be actuated for operating the lifting-bar and thereby opening the door, substantially as specified. 30

2. The combination, with the door A, having 35 the latch B thereon, of the bracket D, having the cross-bar E, and the spindle F above the cross-bar, the lifting-arm G, having a notch, g' , in the upper end to engage the latch B, and the slot g , to receive the spindle F, the angle-arm H, formed on the lower end of the arm G and having its lower end rounded, the angle-lever I, connecting-bar M between the lower arm of the lever and the lower end of the angle-arm H, the pressure-bar N, pivoted 40 to the other end of the angle-lever, and the spring O, to normally hold the said pressure-bar in the raised position, all arranged and operated substantially as and for the purpose specified. 45

In testimony that I claim the foregoing as my own I have hereto affixed my signature in presence of two witnesses.

JOHN DE LAMBERT.
